UNITED STATES PATENT OFFICE.

KNIGHT W. GALE, OF LOS ANGELES, CALIFORNIA.

FLAT-UNFOLDING LUNCH-BOX.

1,129,343.

Specification of Letters Patent. Patented Feb. 23, 1915.

Application filed January 10, 1910. Serial No. 537,352.

To all whom it may concern:

Be it known that I, KNIGHT W. GALE, a citizen of the United States, residing at Los Angeles, in the county of Los Angeles and State of California, have invented a new and useful Flat-Unfolding Lunch-Box, of which the following is a specification.

This invention comprises a lunch box 10 formed of a sheet folding in a novel manner and held by novel means and adapted when not so held to flatten out, thus to form a table top or cover on which the lunch contained in the box may be spread; said table 15 top affording advertising space so that the value of the sheet as a lunch box is secondary to its value for advertising purposes, thus insuring sanitation by inducing the advertiser to furnish the lunch box free to the user, or so cheaply that the user will discard 20 it rather than carry it home for re-use.

The invention also includes a stand designed to hold the structure in box-form while the person preparing the lunch is 25 storing the same in the box.

The accompanying drawings illustrate the invention.

Figure 1 is a perspective view of the lunch box closed and fastened shut as when filled 30 with lunch. Portions are broken away to expose various members of the folded sheet. Fig. 2 is a perspective view of the lunch box open and in a stand ready to be filled. Fig. 3 is a longitudinal mid-section of the box 35 open. Fig. 4 is a transverse section of the box open. Fig. 5 is a view of the sheet after the lunch box has been allowed to flatten out, and the sheet from which it had been formed is ready for use as a table top. Fig. 40 6 is a perspective view of the stand detached. Fig. 7 is a view of the handle fastener detached.

The box is composed of a resilient cardboard sheet scored or creased and slit to 45 form a middle bottom panel 20, two side panels 19, 21, adjacent the bottom panel, two top panels 9 and 10 adjacent the side panels respectively, and two handle flaps 32 and 33, adjacent the top panels, all arranged 50 in a row and united at their edges; two end flaps 30 and 31 at the ends of the bottom panels 20, two pairs of end flaps 22, 25, and 23, 24, united to the ends of the side panels 19, 21; and four locking laps 11, 12, 13 and 55 14 united to the edges of the end laps and folded upon and free from each other be-

neath the top panels and having extended edges engaging the side panels so that when the handle flaps are held together the box retains its box-like shape and when the handle laps are allowed to separate the sheet 60 will fall by its own resiliency into flat form.

The united edges between the panels are marked by parallel creases or scores 15, 16, 17, 18. The united edges between the panels and the end flaps and laps are marked by parallel creases or scores 3, 4. The united edges between the locking flaps and the end laps are formed by extensions of the creases or scores 15, 18. Slits 5, 6, 7, 8, separate between the 70 locking flaps; and slits 26, 27, 28, 29, separate between the end flaps and end laps. The slits 26, 29 are in line with the score 16 and slits 27, 28 are in line with the score 17. The slits 7, 8 are in line with the score 4; 75 and the slits 5 and 6 are in line with the score 3.

The sheet from which the blank is cut may be a parallelogram as shown in Fig. 5.

The fold between the handle flaps 32 and 80 33 and the top panels 9 and 10 are marked by scores 34, 35, respectively, and the handle flaps are provided with lines 36, 37, of perforations which may be of any suitable size and form, as the oblong rectangle shown to 85 make punchings *a*, *b*, that may be subsequently removed for admission of the hand into the handle slots 38, 39, respectively.

Diagonal perforate lines 40, 41, 42, 43 converge to the sheet ends from the slits 5, 6, 90 7, 8 and mark the lines of division between the trimmings 44, and the handles 32, 33. The transverse end perforate lines 48, 49, 50, 51 extend parallel with the transverse scores from the edges of the sheet to the slits 95 5, 6, 7, 8 and mark the division lines between the end trimmings 52, 53, 54, 55 which may respectively be united with the trimmings 44, 45, 46 and 47 as a single piece and may be torn off from the sheet after the same 100 has been printed and scored and removed from the press. That is to say, the slit 5 need not extend to the end of the sheet 1, but may join the line 48; and so with slit 6 and line 49, slit 7 and line 50, and slit 8 and 105 line 60.

The handle flaps are adapted to extend above the box and to hold the side panels against the edges of the locking laps, to retain the sheet in box form, while the handles 11, 12, 13, 14 are held toward each other by hand or by fastener.

The stand *c* consists of a single wire bent reversely from its central body 60 to form two vertical loops forming fingers 61, 62, at opposite ends of the central body 60, which 5 loops connect horizontal transverse limbs 63, 64, respectively, that extend from the sides of loops 61, 62, approximately to the middle of the central body 60 and are there connected with longitudinal limbs 65, 66, that 10 terminate in upright standard fingers 67, 68, the upper ends 69, 70, of which are outwardly bent. The tips of the loops are also outwardly bent as indicated at 71, 72.

In practical use, to form the box, the central end flaps 30, 31, will be bent upward from the bottom panel 20 and then the end laps 23, 24, may be grasped and the side panel 21 bent into upright position and the end laps 23, 24, bent over against the end 15 flaps 30, 31, then the end laps 22, 25, may be grasped and the side panel 19 be bent into upright position with said end laps 22, 25, against the end laps 23, 24, then the open 20 box thus formed may be seated in the stand 25 just described and the box is ready to be filled; after which the locking laps 11, 12, 13, 14, may be bent down to form the cover of the box and the top panels 9 and 10 bent over the same, thus bringing the handle flaps 30 32, 33, against each other where they may be fastened by the key 73 inserted through key holes 74, 75, which may be punched into the handle flaps at any period in the process of manufacturing the box, or thereafter. The 35 handles thus restrain the flattening tendency of the sheet and such tendency co-acts therewith to maintain the shape of the box so long as the handles are held together.

When the lunch is to be eaten, the key will 40 be withdrawn from the key holes and the handles drawn apart and the sheet will then flatten out, thus giving access to the lunch which remains entirely on the sheet and affords a sheet or table-top upon which the 45 lunch may be spread.

The outer edges of the top laps 11, 12, 13, 14 are shown divergent from the inner edges thereof diverging outwardly away from the end flaps so that when the sheet is folded into box form the tips 76 of said divergent 50 outer edges will engage the inner faces of the side members and will be bent or compressed thereby and will thus be not only frictionally held from endwise withdrawal but will also be kept from drooping loosely 55 onto the contents of the box and said top laps will be held in practical parallelism with the bottom panel of the box.

The sheet being made of cardboard has a tendency to spread apart and flatten out 60 and therefore the stand is desirable for use by the person who may wish to fold the sheet into box form. This tendency usually causes the box to open, flatten out and disappear in so far as the box is concerned and 65 the sheet then becomes a table cover. The advertisements which may be applied on the entire upper face of the sheet will then be open to view.

I claim:—

A box composed of a sheet folded to form bottom, sides, ends and top, the ends being formed of flaps and the top being formed of laps, the outer edges of said laps being divergent from the inner edges thereof outwardly from the end flaps so that when the sheet is folded in the box, said divergent edges will engage the inner face of the sides of the box and will be bent or compressed thereby and will thus be kept from drooping 75 loosely onto the contents of the box, and said top laps will be held in practical parallelism with the bottom of the box.

In testimony whereof, I have hereunto set my hand at Los Angeles, California, this 80 31st day of December, 1909.

KNIGHT W. GALE.

In presence of—

JAMES R. TOWNSEND,
L. BELLE RICE.

Corrections In Letters Patent No. 1,129,343.

It is hereby certified that in Letters Patent No. 1,129,343, granted February 23, 1915, upon the application of Knight W. Gale, of Los Angeles, California, for an improvement in "Flat-Unfolding Lunch-Boxes" errors appear in the printed specification requiring correction as follows: Page 1, line 97, strike out the reference-numerals "53, 54, 55"; same page, line 99, strike out the reference-numerals "45, 46, and 47"; and that the said Letters Patent should be read with these corrections therein that the same may conform to the record of the case in the Patent Office.

Signed and sealed this 23rd day of March, A. D., 1915.

[~~SEAL.~~]

J. T. NEWTON,

Acting Commissioner of Patents.
